FOLDING STAND

Filed Jan. 14, 1933

Inventor
Edward Roos
By Gilson, Mann & Co
Attys.

UNITED STATES PATENT OFFICE

EDWARD ROOS, OF RIVER FOREST, ILLINOIS

FOLDING STAND

Application filed January 14, 1933. Serial No. 651,760.

This invention relates to folding stands, or racks, and the principal object of the invention is the provision of a new and improved stand or rack which may be folded, and when in that position will occupy the minimum amount of space.

A further object of the invention is the provision of a new and improved folding stand or service table having novel means for transporting the same from place to place.

Another object of the invention is the provision of a new and improved stand or rack that is provided with movable shelves or supporting members and having novel means for collapsing the supporting legs when certain of said shelves are moved to inoperative position.

Still further objects of the invention are the provision of a new and improved stand, rack, or service table that is inexpensive to manufacture, attractive in appearance, which may be easily and conveniently moved from place to place, strong and durable in construction, and which, when collapsed, will occupy the minimum amount of space.

Other and further objects and advantages of the invention will appear from the following description, taken in connection with the accompanying drawing, in which—

Fig. 1 is a perspective view of the folding stand;

Fig. 2 is a vertical section along the lines 2—2 of Fig. 1 showing the parts in operative position;

Fig. 3 is a similar view but showing the parts in folded position;

Fig. 4 is a section on the line 4—4 of Fig. 2.

It is not unusual in entertainments in private dwellings, as well as in public halls, theaters, churches, lodges, and the like, to require the use of additional tables, stands or other temporary supports which under normal circumstances are not required. It is desirable, therefore, that these supports be

readily accessible, easily moved and set up in the desired position when required, and which, when not in use, may be folded or collapsed to occupy a minimum amount of storage space. It is also desirable that these supports be provided with means whereby they may be conveniently moved when in their extended, or operative, position.

The present invention seeks to provide a support or stand of general utility and that may be easily moved from place to place while in either its folded or its extended position, and also one that may be easily moved while in use.

Referring now to the drawing, the reference character 10 designates generally a stand, or rack, which comprises two pairs of supporting legs or standards 11 and 12 that are hinged together at their upper ends as at 13.

These pairs of legs are connected together by suitable bars. As shown on the drawing, the pair of legs 11 are connected together by bars 13 and the pair of legs 12 are connected together by the bar 14. The upper ends of each pair of legs are preferably, though not necessarily, beveled, as shown at 19 and 21, in Figs. 2 and 3 of the drawing. A suitable cross bar 22 is attached to the upper end of one pair of the legs. As shown, the bar 22 is attached by suitable screws, or the like, to the beveled surface 19 of the pair of legs 11, and is adapted to be engaged by the beveled surface 21 of the upper ends of the other pair of legs when the device is in operative position for limiting the spreading of said pairs of legs.

The two pairs of legs which constitute the support are adapted to support one or more tablets or shelves. In the form of construction shown, which is by way of example only, two tablets 15 and 16 are employed. The tablet 16 is supported at one end by a rod 17 to which the tablet is pivotally connected in any suitable manner. In the form

disclosed, the rod 17 extends through the tablet 16 and is anchored to the legs 11 at its ends. The opposite end of the tablet 16 is adapted to rest on a rod 18 extending between the legs 12, 12 (see Fig. 2) for supporting the free end of the tablet.

Suitable means are provided for holding the tablet in operative position. Any suitable means may be employed. As shown, a spring clip 19 is rigidly connected to one of the legs 12 and has its free end bent as at 20 for engaging the top surface of the tablet for holding the same in lowered position. When it is desired to collapse the stand, the free end of the clip 19 is forced outwardly into a recess 30 in the leg 12 whereupon the tablet may be elevated for collapsing the stand.

Suitable means are provided for causing the collapse of the stand when the shelf 16 is elevated from the position shown in Fig. 2 to that shown in Fig. 3. This is accomplished by providing a link 22' which is pivoted at one end as at 23 to the tablet 16 and has its opposite end pivoted to one of the legs 12, as clearly shown in Figs. 2 and 3 of the drawing. It will be evident from an inspection of said figures that when the free end of the tablet 16 is moved upwardly about the pivot bolt 17, the link 22' will cause the legs 11 and 12 to fold together. If desired, additional tablets may be employed. As shown, one additional tablet 15 is employed. It is pivoted to the legs 11, as by the pivot bar 25, and is adapted to be supported at its free end on a supporting bar 26. The tablet is held in lowered position by a spring clip 27 similar to the clip 19 employed for holding the tablet 16 in lowered position.

When it is desired to collapse the stand, the clips 19 and 27 are forced inwardly and the free ends of the tablets 15 and 16 are moved upwardly until the legs 11 and 12 are brought into contact with each other. The stand may also be collapsed by moving the free end of the tablet 16 upward into contact with the tablet 15 and, after releasing the clip 27, continuing the movement of the free end of the tablet 16 upwardly, which will force the free end of the tablet 15 upwardly and the link 22' will cause the pairs of legs 11 and 12 to be moved into collapsed position, as shown in Fig. 3 of the drawing.

When the stand is in operative position it may be employed as a serving table, a magazine or book rack, or for a support for general utility purposes, and may be easily moved from place to place by means of the cross bar 22.

Furthermore, when made in miniature sizes it is admirably adapted to be associated with doll sets and sold as toys and the like.

It is thought from the foregoing, taken in connection with the accompanying drawings, that the construction and operation of

my device will be apparent to those skilled in the art, and that changes in size, shape, proportion and details of construction may be made without departing from the spirit and scope of the appended claims.

I claim as my invention:—

1. A folding stand comprising a pair of sets of supporting legs, means hinging the upper portions of the sets of legs together, a cross bar connecting the upper ends of certain of the legs together, means for limiting the separation of the free ends of the sets of legs, a tablet, means on one set of legs pivotally connecting said tablet thereto, means on the other set of legs for removably supporting the free end of said tablet, a second tablet, means pivotally connecting one end portion of the last named tablet to one set of legs and means on the other set of legs for removably supporting the opposite end portion of the last named tablet, each of the tablets being a unitary, rigid structure and having its ends extending outwardly beyond the planes of the legs when in operative position.

2. A folding stand comprising a pair of sets of supporting legs, means hinging the upper portions of the sets of legs together, a cross bar connecting the upper ends of certain of the legs together, means for limiting the separation of the free ends of the sets of legs, a tablet, means on one set of legs pivotally connecting said tablet thereto, means for causing the sets of legs to fold together upon movement of said table to inoperative position, a second tablet, means pivotally connecting one end portion of the last named tablet to one set of legs and means on the other set of legs for removably supporting the opposite end portion of the last named tablet, each of the tablets being a unitary, rigid structure and having its ends extending outwardly beyond the planes of the legs when in operative position.

3. A folding stand comprising two sets of supporting legs, each set comprising two legs, a member connecting the legs of each pair together, means connecting the sets of legs together in hinged relation, a unitary, rigid tablet hinged to one of the members and adapted removably to engage the other member and be supported thereby in horizontal position and link means pivoted to said tablet and one of the legs to which the last named member is connected for causing said tablet to move to vertical position when said sets of legs are folded together, said tablet extending outwardly at each end beyond the plane of the adjacent set of legs.

4. A folding stand comprising a pair of sets of supporting legs, means hinging the upper portions of the sets of legs together, a cross bar connecting the upper ends of certain of the legs together, means for locking the sets of legs in extended relation, a tablet, means on one set of legs pivotally connecting

said tablet thereto, means on the other set of legs for removably supporting the free end of said tablet, a second tablet, means pivotally connecting one end portion of the 5 last named tablet to one set of legs and means on the other set of legs for removably supporting the opposite end portion of the last named tablet, each of the tablets being a unitary, rigid structure and having its ends 10 extending outwardly beyond the planes of the legs when in operative position.

In testimony whereof, I affix my signature.
EDWARD ROOS.
